W. K. SCHAUWEKER,
GASOLENE VENDING APPARATUS,
APPLICATION FILED AUG. 15, 1913.

1,241,889.

Patented Oct. 2, 1917.

UNITED STATES PATENT OFFICE.

WILLIAM K. SCHAUWEKER, OF CLEVELAND, OHIO.

GASOLENE-VENDING APPARATUS.

1,241,889.

Specification of Letters Patent.

Patented Oct. 2, 1917.

Application filed August 15, 1913. Serial No. 784,992.

To all whom it may concern:

Be it known that I, WILLIAM K. SCHAUWEKER, a citizen of the United States, residing at Cleveland, in the county of Cuyahoga and State of Ohio, have invented certain new and useful Improvements in Gasoline-Vending Apparatus, of which the following is a specification.

This invention relates to apparatus for handling fluids generally, but more particularly is designed for the purpose of dispensing gasolene.

More specifically the invention comprises a tank or reservoir buried under ground and provided with a measuring tank connected by a discharge pipe with a suitable discharge hose arranged in a standard above the sidewalk, together with suitable mechanism for discharging gas, preferably carbon dioxide, through a gas delivery pipe extending from the standard into the measuring tank adapted to elevate the liquid in the measuring tank through the discharge pipe and into the discharge hose, mechanism being also provided for manipulating the gas container or cartridge which is to be inserted into the machine for supplying gas for the purpose above outlined.

The invention may be further briefly summarized as consisting in the construction and combination of parts hereinafter set forth in the following description, drawings and claims.

Referring to the drawings, Figure 1 is a sectional view of the apparatus; Fig. 2 is a sectional view of the head of the standard; Fig. 3 is a sectional view of the measuring tank; Fig. 4 is a sectional view of a portion of the apparatus within the head of the standard; and Fig. 5 is an enlarged detail view of the container opening device.

In carrying out my invention any preferred form and construction of parts may be employed so long as they possess the necessary characteristics, but I have shown one embodiment which is highly effective in operation, and in such construction, 1 represents a suitable standard having a head 2 of sufficient size to receive the mechanism. Below the ground is a storage tank 3 for re-

ceiving the liquid. This tank is provided with a downwardly extending portion 4 in the bottom for receiving a measuring tank 5, the latter being of a capacity such that it will hold a pre-determined quantity of liquid. 55 The measuring tank 5 is provided with a gas inlet pipe 6 and a liquid discharge 7, the latter extending to a point near the bottom of the tank. The top of the tank is provided with suitable openings 8 communicating with a valve casing 9 having a partition 10 therein. This partition is provided with a valve seat 11 adapted to receive a valve 12 connected to a stem 13 upon which a float 14 is mounted. The stem 13 passes through an 60 opening in the top of the measuring tank and also in a web or spider 15 arranged above for partition 10. The valve casing 9 is provided with an opening 16 for the passage of the liquid into the same and into the 65 measuring tank.

The arrangement of the measuring tank and the valve mechanism is such that in the absence of pressure the liquid in the main storage tank 3 flows down through the opening 16 through the valve seat 11 and into the measuring tank until it is filled to the point of raising the float 14 when the valve 12 seats and prevents the further entrance of liquid into the tank and discharge pipe 7. 75 The valve 12 remains seated while the mechanism is inactive by reason of the float raising itself in the valve mechanism so that the latter is seated, and when gas pressure is applied to the measuring tank this valve 12 is 80 held closed by the pressure of the gas on its underside, the weight of the parts being insufficient to unseat this valve against the gas pressure while the apparatus is discharging but as soon as the pressure is led from the 85 measuring tank, then the weight of the parts is sufficient to cause the valve 12 to fall, and further the weight of the liquid in the main tank upon this valve tends to unseat it.

The discharge pipe 7 extends up into the 95 standard 1 and at its upper end is connected to a suitable discharge hose 17, which passes over a roller 18 and is normally drawn within the head and the standard by means of a weight 19 connected to a roller 20 arranged 100

on the hose. The pipe 6 also extends up into the standard and is provided with an L connection 21 having a flared mouth 22 at the open end thereof. Within the flared 5 mouth 22 is a spider 23 having a projection 24 extending outward within the mouth for a purpose to be described.

Suitable cartridge or gas container manipulating mechanism is provided in the 10 head and it comprises a chute 25 having an opening 26 extending out through the side wall of the head and leading to a pocket 27 in a carrier 28 which is mounted in a suitable guide 29 secured to the inner wall of 15 the head. The guide 29 is provided with a slot 30 for receiving a finger 31 of a lever 32 fulcrumed in the casing. The finger 31 extends into an opening 33 in the carrier 28 and the arrangement is such that the carrier is moved in its guide by the lever. Just 20 forward of the end of the chute 25 is a shoe 34 having a curved face 35 and another curved face 36 for purposes to be described. This shoe is mounted on a stem 37 slidably 25 supported in a hollow projection 38 forming a part of the head, and a pin 39 extending through a slot 40 and into the stem 37 serves to limit the movement of the shoe. The pocket 27 is adapted to receive a suitable 30 cartridge or gas container 41 provided with a suitable mouth 42 having a valve seat 43 therein co-operating with a valve 44 within the cartridge. This valve is normally held shut by the charge of gas within the 35 cartridge or gas container and is opened by the projection 24.

In operating the device, assuming that the storage tank 3 contains a supply of liquid the operator inserts a cartridge or gas container 40 through the opening 26 into the chute 25 where it passes by gravity down into the pocket 27, a cartridge being withdrawn and in the position shown in Fig. 4. The operator then raises the lever 32 and causes the 45 cartridge to engage the curved face 35 of the shoe 34 raising the same. The cartridge then passes on and engages in the mouth 22 of the connection 21, the pin 24 engaging the valve 44 and opening the same, with the result 50 that the gas stored in the cartridge passes down through the pipe 6 into the measuring tank 5 and causes the liquid in the measuring tank to pass up through the pipe 7 and out through the delivery hose 17. 55 As soon as the flow of liquid ceases, then the operator returns the lever 32 to normal position when the curved face 36 of the shoe 34 engages the rear end of the cartridge and holds it permitting the carriage to move 60 from under the same when the cartridge will be discharged by the spring into the head of the standard. In the meantime the float 14 has dropped and a fresh supply of liquid has entered the measuring tank and closed

the valve 12 when the machine is ready for 65 another operation.

Having described my invention, I claim:—

1. A liquid vending apparatus, comprising a main supply tank, a measuring tank communicating therewith, means for supporting a cartridge containing gas under pressure, and an unrestricted conduit providing free and open communication between said cartridge and measuring tank for discharging the gas from said cartridge into said measuring tank to expel the liquid therefrom. 70

2. A liquid vending apparatus, comprising a main supply tank, a measuring tank communicating therewith, an unrestricted conduit providing free and open communication to said measuring tank, and means for connecting a cartridge containing gas under pressure to said conduit thereby opening said cartridge and causing the gas therein to flow to said measuring tank and expel the liquid therefrom. 75

3. A liquid vending apparatus, comprising a main supply tank, a measuring tank communicating therewith and arranged to be completely filled by gravity therefrom, means for closing communication between said two tanks upon filling of the measuring tank, an unrestricted gas delivery pipe connected to the measuring tank, means for supporting a cartridge containing gas under pressure, and means for directly connecting the cartridge to said pipe for discharging the gas into the measuring tank to expel the liquid therefrom. 90

4. Vending apparatus comprising a storage tank, a measuring tank connected therewith, means for supplying a predetermined amount of liquid from the storage tank to the measuring tank, a liquid discharge pipe connected to the measuring tank, a gas delivery pipe connected to the measuring tank, a cartridge receiving carriage, means for delivering a cartridge to said carriage, and means for moving the cartridge into engagement with the gas delivery pipe and thereby establishing communication between the two. 100

5. Vending apparatus comprising a storage tank, a measuring tank connected therewith, means for supplying a predetermined amount of liquid from the storage tank to the measuring tank, a liquid discharge pipe connected to the measuring tank, a gas delivery pipe connected to the measuring tank, a cartridge receiving carriage, means for delivering a cartridge to said carriage, means for moving the cartridge into engagement with the gas delivery pipe and thereby establishing communication between the two. 110

6. A liquid vending apparatus, comprising a main storage tank, a measuring tank connected therewith, means for closing the connection between said two tanks upon filling of the measuring tank, said means compris- 125

ing a float valve adapted to close when the measuring tank is full and upon discharge of liquid from the measuring tank to be held closed by the pressure therein, means for supporting a cartridge containing gas under pressure, an unrestricted conduit providing free and open connection to the measuring tank, and means for connecting said

cartridge to said conduit to discharge liquid from said measuring tank.

In testimony whereof I affix my signature in presence of two witnesses.

WILLIAM K. SCHAUWEKER.
